UNITED STATES PATENT OFFICE.

EUGENE V. DAILY, OF CHICAGO, ILLINOIS, ASSIGNOR TO JAMES B. CLOW & SONS, OF CHICAGO, ILLINOIS, A CORPORATION OF ILLINOIS.

RADIATOR.

Application filed March 27, 1926. Serial No. 97,860.

This invention pertains to radiator construction and more particularly to the construction of a section for radiators that are directly fired; that is, for that type of radiator which is adapted to replace the ordinary radiator in a steam or hot water heating system or to be operated independently or exclusively of such system. The general character and uses of a radiator of this type, to 5 the sections or loops of which my invention may be applied is illustrated and described in Patent #1,342,509 dated June 8, 1920 and in my prior Patent No. 1,580,651, dated April 13, 1926, both of which are assigned to the assignee of the present application.

The radiator to which the present form of my invention is applied is primarily adapted to be heated by gaseous fuel and is not equipped with the usual connections for delivering the heated products of combustion into a chimney, flue or stack after use. Instead, the heated products of combustion are preferably used to initiate the heating of the room or the like in which the radiator is situated and thereafter to supplement the heating effect of the steam generated or the water heated in the radiator, on such room. Maximum efficiency is thus secured.

However, it has been found that with radiators so constructed certain difficulties and objectionable features are encountered. When, for instance, such radiator be placed beneath and adjacent a window, the heated gases are apt to scorch, if not set fire to the window curtains or drapings. Sometimes a quantity of fuel gas is permitted to escape before a match is applied to the burner to ignite it. The unburned fuel gas rises upwardly between the radiator sections or loops and when an attempt is made to ignite the fuel gas at the burner, the flame follows the same upward path igniting the gaseous fuel which has risen above the sections. The danger is apparent if filmy curtains or drapes overhang the radiator.

But the housewife is also concerned about the dirt and soot which drops from the burner chamber of the present type of gas-fired radiator onto the floor or carpet beneath the radiator. This often happens because it has been considered necessary for numerous reasons to place the openings for admission of air to the burners to support combustion, directly and centrally fore and aft beneath the radiator, and, as some soot forms above the burner and

drops therefrom from time to time, it follows 55 that such soot and dirt falls upon the floor.

With my invention the objectionable features above enumerated and others are entirely obviated. Any unburned gases and the heated gases rising from the burner pass between the several sections of the radiator and are deflected forwardly into the room and prevented from rising immediately and directly upward where they might detrimentally affect objects suspended over the radiator. The 60 radiator sections are also so arranged and constructed that any soot and dirt which may, in the course of time, accumulate within the combustion chamber or above it, may not fall through the necessary vent openings in the 65 bottom of the radiator through which air to support combustion is admitted.

The primary objects of the invention, therefore, are to provide radiator sections or loops or radiators of the character described with 70 simple but effective means for carrying out or accomplishing the foregoing desirable ends with a minimum of construction and labor costs and with a maximum of efficiency. It will in this connection be noted that the heating effect of a radiator built in accordance with the invention will be initiated by the hot gases or products of combustion which are thrown out into the room away from the wall or other place adjacent which the radiator may be positioned and the heating effect of the water heated or the steam generated in the radiator enhanced so long as the burner remains lighted, all of which contribute to quick and steady heating of the room or chamber 80 within which the radiator may be located.

Many other objects and advantages including the details of construction and operation should be readily appreciated after perusal of the description and claims and after viewing 85 the attached drawings in which:

Fig. 1 is a front elevation of a radiator loop assembly, the loops being constructed in accordance with what is at present a preferred form of the construction.

Fig. 2 is a section taken on the line 2—2 of Fig. 1.

Fig. 3 is a section taken on the line 3—3 of Fig. 1.

Fig. 4 is a section taken on the line 4—4 of Fig. 2 and

Fig. 5 is a section taken on the line 5—5 of Fig. 2.

105

In the drawing the radiator is shown as composed of end sections or loops generally designated 2 and 3 each provided with legs 4 and 5 for their support as well as the support of the intermediate sections or loops generally designated 6 of which but three are shown in Fig. 1. Each section or loop, in the preferred form, is a casting cored out to provide a top header chamber 7, a bottom header chamber 8 and a plurality of vertical columns 9, 10, 11 and 12 connecting the top and bottom header chambers.

Each intermediate section on both sides of the top and bottom header chambers and each end section on the side of the top and bottom headers adjacent an intermediate section (in case of two sections only, the sides of the headers of the end sections adjacent the opposite end section) are bored out, preferably with a tapered bore 13 for the reception of a nipple 14, whereby the sections may be interconnected in water tight engagement. The bottom header terminates in a wall 15 extending transversely across the section and from end to end thereof to provide, with the wall of the shell 16 integral with the walls of the end columns 9 and 12, a combustion chamber 17 within which the gas or other fuel burner is adapted to be situated. The lowermost portion of the shell 16, preferably centrally between the front and rear of the radiator sections, is cut away, as indicated at 18, for the admission of air to the combustion chamber 17, but since soot and dirt normally collecting on the bottom of the wall 15 and elsewhere within the radiator drops under its own weight or after slight vibration it would, by reason of the opening provided by the cut away portion 18 directly therebelow, fall through the opening onto the floor. To overcome this and prevent the occurrence of this objectionable action, I prefer to cast a plate or baffle 19 integral with the shell 16 and over, but spaced from, the lower portion of the shell wall containing the vent opening and with its ends 20 extending over and beyond the extreme ends of the vent opening, so that soot or dirt falling from the wall 15 or from elsewhere in the radiator will be caught upon the baffle or plate 19 or at the ends of the wall of the shell 16 and out of the way of the vent openings. This plate also serves another purpose in that it is more desirable to have air for the support of combustion within the chamber entering at the opposite sides of the burner, not shown, but which as is usual extends longitudinally and centrally through the combustion chamber sections, than it is to have the air entering in one column directly beneath the burner.

As has heretofore been noted, it is desired to direct the heated gases of combustion, after they have had an opportunity to heat

the water or other fluid contained within the radiator and thereby expended some of their energy, out into the room or other place in which the radiator is located. It is also necessary that the combustion chamber be substantially closed between the several sections of the radiator for obvious reasons.

To this end each intermediate section or loop is provided with a rib 21 on each side and each end section with such a rib on but one side. These ribs preferably extend from some point designated 22 outwardly along the bottom header 8 to a point adjacent the front edge of the section, thence downwardly across the header and following the contour of the shell 16, rise again adjacent the back edge of the radiator section, approach for a short distance toward the point 22 of the beginning of the rib and thence curve upwardly, as shown at 23 along the column 10 to the top header nipple connection 13' where it is joined thereto, as shown at 24. Between the points 23 and 24 each rib may have a flat-top face, but from the point 22 to the point 23 one rib 21 is cut away for a portion of its width or thickness on one side, as shown at 25, while the rib on the opposite side of the section is cut away at the opposite side as shown at 26. In other words, the portions of the ribs about the combustion chamber section 17 are so formed on opposite sides of the radiator section that they will interlockingly engage with the same portions of the rib of the adjacent section and thereby provide a substantially tight connection for the combustion chamber. The end sections of course, will be provided with one rib each which will be formed to correspond to the rib of the adjacent face of the adjacent section, while any suitable arrangement may be made for closing the ends of the combustion chamber in the end sections whereby the radiator may be provided with a fuel burner and pilot light etc., as desired. These latter items form no part of the invention hereof and being well known are deemed to need no further description.

The lower header coupling, generally designated 27, is preferably formed in the shape shown in Fig. 2 and complemental couplings of adjacent sections or loops cooperate together and with what I shall term auxiliary ribs 28 to aid in directing the gases without eddies upwardly between the points 22 and 23 of the ribs 21. As the gases rise along the columns between and through the sections they effect heating of the sections and when they reach the upper portions of the columns the upper portions of the ribs 21 together with the nipple coupling connections 13' serve to direct them forwardly into the room within which the radiator is situated. The adjacent sections in connection with the ribs 21 and the top header cou-

plings 13' provide openings giving a register effect as shown at A, B, C and D in Fig. 1.

From the foregoing it will be appreciated that I have devised a unique radiator section with numerous advantages, the illustrated arrangements for the attainment of which are susceptible of modification and change without departure from the spirit of the invention and the scope of the appended 10 claims.

I claim:

1. A radiator of the character described comprising a plurality of loops including a end loops, each of said loops comprising a 15 plurality of hollow columns and a hollow bottom header with the columns open to said header, a continuous shell integral with the walls of said columns and below said header providing a section of a combustion 20 chamber and having a portion of its bottom wall cut away to provide an opening through the bottom thereof, a baffle connected to said shell over said opening whereby air entering said chamber through said opening will 25 be directed to the chamber at the sides thereof, and a rib on said shell about a portion of the combustion chamber on the side of the shell normally disposed toward the shell of the adjacent loop, said rib being adapted 30 to abut, throughout its length, the rib on the adjacent section.

2. A radiator of the character described comprising a plurality of loops, each of said loops including a plurality of hollow columns, a hollow bottom header into which said columns open, a shell integral with the walls of certain of the columns, extending below said header and providing a section of a combustion chamber, one of the loops having an opening through the wall of the shell 40 substantially centrally of the bottom thereof, and a baffle connected to said shell of the loop having the opening, beneath said chamber and projecting over and beyond the margins of the opening whereby soot and the like collected in said chamber will be prevented from falling directly through said opening.

3. A radiator of the class described comprising a plurality of loops, certain of said 50 loops each being provided with a plurality of hollow columns including an intermediate column, a hollow bottom header into which said columns open and a shell integral with the walls of the outside columns, extending 55 below said header and providing a combustion chamber with an opening thereto through the shell substantially centrally of the bottom thereof, and each end loop having on one side and each intermediate loop 60 having on both sides, a rib projecting laterally therefrom toward, and adapted to abut against, the rib of the adjacent loop, said rib extending from a point adjacent the top of 65 the combustion chamber downwardly about

said chamber and upwardly and forwardly from the rear of said chamber to a place adjacent the top of the radiator loop.

4. A radiator of the class described comprising a plurality of loops, certain of said loops each being provided with a plurality of hollow columns including an intermediate column, a hollow bottom header into which said columns open and a shell integral with the walls of the outside column, extending 75 below said header and providing a combustion chamber with an opening thereto through the shell substantially centrally of the bottom thereof, a baffle connected to each said shell having an opening through its 80 bottom, said baffle projecting over and beyond the margins of the opening whereby soot and the like collecting in said chamber will be prevented from falling directly through said opening and each end loop having on one side and each intermediate loop having on both sides a rib projecting laterally therefrom, toward, and adapted to abut against, the rib of the adjacent loop, said rib extending from a point adjacent the top 85 of the combustion chamber downwardly about said chamber and upwardly and forwardly from the rear of said chamber to a place adjacent the top of the radiator loop and terminating in a portion directed toward the front of the section.

5. In a radiator of the character described, a loop comprising, a plurality of hollow columns, a hollow bottom header into which said columns open, a shell integral with the walls of certain of said columns, extending below said header and providing a combustion chamber with an opening thereto substantially centrally of the bottom thereof and a baffle connected to said shell beneath said header and projecting over and beyond the margins of said opening whereby soot and the like collecting in said chamber will be prevented from falling directly through said opening.

6. In a radiator of the character described, a loop comprising, a plurality of hollow columns including outside columns and an intermediate column, a hollow bottom header into which said columns open and a shell integral with the walls of the outside columns, extending below said header and providing a combustion chamber with an opening thereto substantially centrally of the bottom thereof, a rib projecting laterally from each side of 115 said radiator loop and toward, and adapted to abut against, a corresponding rib of an adjacent loop, said ribs each extending from a point adjacent the top of the combustion chamber downwardly about said chamber 120 and upwardly and forwardly from the rear of said chamber along said intermediate column to a place adjacent the top of the radiator loop and spaced from the rear thereof.

7. In a radiator of the character described, 130

- a loop comprising, a plurality of hollow columns including outside columns and an intermediate column, a hollow bottom header into which said columns open and a shell integral with the walls of the outside columns, extending below said header and providing a combustion chamber with an opening thereto substantially centrally of the bottom thereof, a rib projecting laterally from each side of said radiator loop and toward and adapted to abut against the corresponding rib of an adjacent loop, said ribs each extending from a point adjacent the top of the combustion chamber downwardly about said chamber and upwardly and forwardly from the rear of said chamber along said intermediate column to a place adjacent the top of the radiator loop and providing with an adjacent and abutting rib a wall terminating toward the front of the radiator, the said shell having an integral baffle between the bottommost portions of the ribs, beneath said header and projecting over and beyond the margins of the opening through said shell whereby air will flow indirectly into said combustion chamber and soot and the like collecting in said chamber above said baffle will be prevented from falling downwardly through said opening.
8. A radiator of the class described comprising a plurality of loops, certain of said loops each being provided with a plurality of hollow columns including an intermediate column, a hollow bottom header into which said columns open and a shell integral with the walls of the outside columns, extending below said header and providing a combustion chamber with an opening thereto through the shell substantially centrally of the bottom thereof, and each end loop having on one side and each intermediate loop having on both sides, a laterally projecting rib about the bottom and sides of said chamber and extending partially over the top toward the front side from the rear side of said chamber adapted to abut against the corresponding rib of an adjacent loop, and a connection from the top of each loop to its adjacent loop intermediate the front and rear of the loop.
- 50 9. A radiator of the class described comprising a plurality of loops, certain of said loops each being provided with a plurality of hollow columns including an intermediate column, a hollow bottom header into which said columns open and a shell integral with the walls of the outside columns, extending below said header and providing a combustion chamber with an opening thereto through the shell substantially centrally of the bottom thereof, and each end loop having on one side and each intermediate loop having on both sides, a laterally projecting rib about the bottom and sides of said chamber and extending partially over the top toward the front side from the rear side of said
- chamber adapted to abut against the corresponding rib of an adjacent loop, and a nipple connection boss on one side of each end loop and both sides of each intermediate loop and intermediate the front and rear sides and adjacent the top thereof, adjacent nipple connection bosses being adapted to abut one another.
- 10 11. A radiator comprising a plurality of loops, each loop including a plurality of hollow columns, a hollow bottom header into which said columns open and a shell integral with the walls of certain of said columns, extending below said header and providing a section of a combustion chamber, each of the loops having an opening through the bottom wall of its shell, and a baffle over and above each opening.
- 15 12. A radiator comprising a plurality of loops, each loop including a plurality of hollow columns, a hollow bottom header into which said columns open, a shell integral with the walls of certain of said columns, extending below said header and providing a section of a combustion chamber, one of the loops having an opening through the bottom wall of its shell, and a baffle over and in spaced relation to said opening.
- 20 13. A radiator comprising a plurality of loops, several adjacent loops each including a plurality of hollow columns, a hollow bottom header into which said columns open and a shell connected to the outside columns, extending below and in spaced relation to said header and providing a section of a combustion chamber, each of said loops having a portion of the bottom wall of its shell cut away to provide an air opening to the combustion chamber, and baffles in the combustion chamber extending over the marginal edges of each opening in spaced relation thereto.
- 25 14. A radiator comprising a plurality of loops, several adjacent loops each including a plurality of hollow columns, a hollow bottom header into which said columns open, a shell connected to the outside columns, extending below and in spaced relation to said header and providing a section of a combustion chamber, at least one of said loops having a portion of the bottom wall of its shell cut away to provide an air opening to the combustion chamber, and a baffle connected to said shell having said opening, over and in spaced relation to the said opening.
- 30 15. A radiator comprising a plurality of multi-columned loops secured together, each loop having a hollow bottom header in connection with its columns and a shell extending about a space below the header to provide a combustion chamber section, adjacent shells abutting one another at their edges down the sides of the combustion chamber and for at least a portion of the distance across the bottom thereof to provide a substantially in-

- closed combustion chamber composed of a plurality of sections, the shells of said loops each having an aperture in the bottom walls thereof for admission of air to the combustion chamber, and baffles integral with the walls of the shells over and in spaced relation to each aperture.
15. A radiator comprising a plurality of multi-columned loops secured together, several adjacent loops each having a hollow bottom header in connection with its columns, a shell extending about a space below the header to provide a combustion chamber section, adjacent shells abutting one another at their edges down the sides of the combustion chamber and for at least a portion of the distance across the bottom thereof to provide a substantially inclosed combustion chamber composed of a plurality of sections, the shells of at least two of said adjacent loops having an aperture in the bottom walls thereof for admission of air to the combustion chamber, and a baffle connected to each shell having an aperture, over and in spaced relation to such aperture within the space inclosed by said shell.
16. A radiator of the class described comprising a plurality of loops, some of said loops each being provided with a plurality of hollow columns including an intermediate column, a hollow bottom header into which said columns open and a shell integral with the walls of the outside columns, extending below said header and providing a combustion chamber having an opening thereto through a portion of the shell at the bottom thereof, a connection from the top of each loop to its adjacent loop intermediate the front and rear of the loop, and each end loop having on one side and each intermediate loop having on both sides a laterally projecting rib extending rearwardly from said connection over said combustion chamber and thence in a downward direction for predetermined distances along a column of the loop.
17. A radiator of the class described comprising a plurality of loops, some of said loops each being provided with a plurality of hollow columns including an intermediate column, a hollow bottom header into which said columns open and a shell integral with the walls of the outside columns, extending below said header and providing a combustion chamber with an opening thereto through the shell at the bottom thereof, a nipple connection boss on one side of each end loop and both sides of each intermediate loop and intermediate the front and rear sides and adjacent the top thereof, adjacent nipple connection bosses being adapted to abut one another, and each end loop having on one side and each intermediate loop having on both sides a laterally projecting rib extending rearwardly from said connection boss over said combustion chamber and thence in a downward direction for a predetermined distance along a column of the loop.
18. A radiator of the class described comprising a plurality of loops, some of said loops each being provided with a plurality of hollow columns including an intermediate column, a hollow bottom header into which said columns open and a shell integral with the walls of the outside columns, extending below said header and providing a combustion chamber having an opening thereto through a portion of the shell at the bottom thereof, baffle means within the space included within the shell and over and in spaced relation to each opening, a connection from the top of each loop to its adjacent loop intermediate the front and rear of the loop, and each end loop having on one side and each intermediate loop having on both sides a laterally projecting rib extending rearwardly from said connection over said combustion chamber and thence in a downward direction for a predetermined distance along a column of the loop.
19. A radiator of the class described comprising a plurality of loops, some of said loops each being provided with a plurality of hollow columns including an intermediate column, a hollow bottom header into which said columns open and a shell integral with the walls of the outside columns, extending below said header and providing a combustion chamber with an opening thereto through the shell at the bottom thereof, baffle means within the space included within the shell and over and in spaced relation to each opening, a nipple connection boss on one side of each end loop and both sides of each intermediate loop and intermediate the front and rear sides and adjacent the top thereof, adjacent nipple connection bosses being adapted to abut one another, and each end loop having on one side and each intermediate loop having on both sides a laterally projecting rib extending rearwardly from said connection boss over said combustion chamber and thence in a downward direction for a predetermined distance along a column of the loop.

In witness of the foregoing I affix my signature.

EUGENE V. DAILY.
